ATOMIZER

Gladys de Maublanc, Paris, France, assignor to
 Elizabeth Arden, Inc., New York, N. Y., a corporation of New York

Application January 17, 1934, Serial No. 707,022
 In France June 9, 1933

1 Claim. (Cl. 299—88)

The present invention relates to toilet atomizers of the type wherein an atomizer head, which is fitted on to a bottle or like receptacle, comprises an atomizing orifice and an air blowing orifice.

5 In accordance with this invention, a plug is provided which may be fitted into the air blowing orifice in such manner as to close it hermetically, the plug being provided with a rod-like extension, the end of which hermetically closes 10 the atomizing orifice, interiorly of the latter.

A further object of the present invention is to provide a construction of atomizer which is particularly adapted to be used in connection with closure means of the character described.

15 Other details and advantages of the invention will be evident from the detailed description thereof hereinafter set forth, particular reference being had to the accompanying sheet of drawing, wherein:

20 Fig. 1 is a vertical axial sectional view through an atomizer constructed according to the present invention;

Fig. 2 is a front elevational view of a plug, in accordance with the invention;

25 Fig. 3 is a view, partly in elevation and partly in section, showing the plug of Fig. 2 inserted in place in the head of the atomizer of Fig. 1.

Similar reference characters designate corresponding parts throughout the several figures of 30 drawing.

The atomizer, illustrated on the drawing, comprises a bottle or like receptacle 1, a ferrule 3 being sealed or otherwise securely fastened to the bottle or receptacle neck. Atomizer head 4 is threaded 35 mounted on the ferrule 3. Threaded into a central boss or extension 5 is a tubular member 6, from the lower end of which a glass aspirating tube 7 depends. The upper end of the tubular member 6 fits into a central bore 8 of the head 4, and is provided with an orifice 9 which opens into 40 the upper portion of bore 8. A resilient annulus 10 is interposed between the top of the ferrule 3 and the bottom of head 4 in order to assure the air tight character of the joint between these 45 parts.

The central bore 8 opens, at the upper end thereof, into a transverse bore 11 which terminates at one end, at one side of the head, in a small atomizing orifice 12, and opens at the other side of the head into an annular channel 13. The blower tube 14 is threaded at 15, on this side, into bore 11, and extends inwardly to a point adjacent orifice 12, terminating opposite 50 the latter in a corresponding orifice 16. Orifice 55

16 is formed in an end piece 17 which is threaded into the end of tube 14.

Head 4 further comprises an air aspirating channel 18, one end of which opens into the bottom of the head, at 19, while the other end 5 opens into the bottom of channel 13, at 20.

Air is supplied to the atomizer by means of a pear-shaped bulb 21, the outlet or opening of which is clamped in the bottom of a fitting 22 by means of clamping nut means 23. The latter 10 is screwed onto a threaded hollow central pin 24 which extends downwardly across the fitting 22. The central bore 25 of pin 24 communicates, through a lateral orifice 26 and an aligned orifice 27 in the fitting, with a lateral tapped bore 28, 15 into which the outer end of the tube is threaded.

The atomizer operates in substantially conventional manner, and a detailed description of the mode of operation is therefore unnecessary.

When it is desired to remove the bulb and 20 to close the bottle so that the contents thereof cannot be spilled, either into the exterior or into the bulb, even if the atomizer and its contents be turned upside down, as sometimes happens in a traveling bag or the like, it has heretofore 25 been customary to unscrew the atomizer head and to replace it by a stopper adapted tightly to close the opening of the bottle. This procedure involves a number of disadvantages. In the first place, it is necessary to provide the 30 atomizer with a removable head; the remaining assembly of head and bulb, interconnected by means of a tube, is very prone to be broken or otherwise damaged; with atomizers wherein the bulb is applied against a plane surface of the 35 bottle, it is first necessary to move the bulb to an out-of-the-way position to enable it to be turned around the bottle in order to unscrew the head; the bottle is completely opened each time that the head is replaced by the plug or 40 stopper, or vice versa, thus involving an appreciable loss of perfume due to evaporation; finally, the stopper constitutes an additional piece, the appearance of which must have due regard to size, and which is comparatively expensive. 45

In accordance with the present invention, it is the tube 14 which is unscrewed, together with the bulb, from the air blowing orifice 15, the tube being replaced by the plug illustrated in 50 Fig. 2.

This plug consists of a rod 29, one end of which is provided with a head 30, and the other end with a partially encased rubber plug 31. Adjacent head 30, the rod 29 is threaded at 32 55

to correspond with the threads at the orifice 15 of the atomizer head 4. A resilient washer 33, the diameter of which is somewhat less than that of the channel 13 which surrounds orifice 15, is mounted on rod 29 against head 30, in which it is partly housed.

The plug, thus constituted, is introduced into the atomizer head 4, as shown on Fig. 3. Rod 29 fits into bore 11, threaded portion 32 is threaded into orifice 15, and plug 31 is locked against orifice 12, partly penetrating thereinto and tightly and hermetically closing it, while at the same time washer 33 is clamped in channel 13, hermetically closing orifice 15 as well as orifice 20.

It will be noted that, in this manner, the bottle is hermetically sealed by the manipulation of one small part, use of which eliminates all the aforementioned disadvantages.

It will be understood that the invention has hereinbefore been disclosed purely by way of example only, and that numerous details thereof may be modified without departing from the inventive spirit.

Having disclosed the invention, what is claimed is:

Atomizer construction including a receptacle and an atomizer head mounted thereon, said head being provided with an atomizing orifice, an air blowing orifice and an air aspirating orifice, an integral member closed at its outer end and separable from said head and shaped to simultaneously seal all three orifices, one end of said member constituting an internal closure for said atomizing orifice, the other end of said member constituting an external closure for said air aspirating orifice, an intermediate portion of said member extending through said air blowing orifice, said integral means consisting of an elongated rod-like body with an enlarged head at one end thereof, a resilient plug partly housed in said body at the other end thereof and a resilient washer being disposed adjacent said enlarged head and partly encased thereby, said resilient plug constituting an element of said internal closure and said resilient washer constituting an element of said external closure.

GLADYS DE MAUBLANC.
